UNITED STATES PATENT OFFICE

2,099,136

TRACTION WHEEL

Karl Johan Engelbert Nilson, Schenectady, N. Y.

Application February 19, 1936, Serial No. 64,664

3 Claims. (Cl. 301—44)

This invention relates to new and useful improvements in traction wheels, and it has for its object to provide a construction which will make it possible to use a motor sled with no diminishing effect as to speed and manipulation on account of the condition of the ground, or road, that is, whether the latter is covered by ice or snow.

Thus this present invention may be said in some respects to be an improvement on, and variation of an invention, for which the U. S. patent, No. 1,574,924, has been granted to me.

As my new construction is comparatively simple, the cost of manufacturing should be proportionately low.

With the above and other objects in view, this invention consists of the novel features of construction, combination and arrangement of parts hereinafter fully described, claimed and illustrated in the accompanying drawing forming part of this application, and in which similar characters of reference indicate corresponding parts in all views, and in which:

Figure 1 shows in detail and detached a shoe member, a number of which are secured to the front wheel of my device.

Figure 2 shows, in part, my said shoe device secured to a wheel; while

Figure 3 shows, in detail, the relative arrangement of one of said shoes upon a wheel; and

Figure 4 represents another view, in detail, of the shoe proper.

Referring more particularly to the drawing, a single unit, or shoe member has been shown detached in Figure 1, while the relative arrangement of a shoe member to the wheel has been shown in Figure 3, and a number of shoe members have been shown attached to part of a wheel in Figure 2.

The said shoe member comprises a downwardly depending bifurcated portion 21, each side of which portion is provided with an aperture 22 adapted to receive therein a screw or rivet 23, when, as shown in Figure 2, the shoe is attached to the edge of the wheel 20. The opposite end of said bifurcated portion terminates in a gripping member 24, which consists of a block portion cut out in a substantial H-shaped form in order to give this part durability and strength, and at the same time provide said part with as many sharp engaging edges as possible, without, as said above, weakening the strength of the construction. While said gripping member may be made integral with the bifurcated portion, it may also be made as a special unit provided with

a shank, which may then be threaded into, or in any other way secured to said bifurcated section.

A V-shaped tapered portion 25 forms an integral part of said shoe member, while short rods 26, 26, only one of which can be seen in Figure 1, depend from said V-shaped member near the free ends thereof, and are also made integral with the latter. At the lower end of each rod 26 and forming an integral part therewith, is a short cylindrical tube 27 formed with collars 44 thereon and, adapted to be fastened on to the wheel proper, one tube upon each side thereof, while a bolt, or rivet 28, secures said tube members integrally to the wheel, as shown in Figure 2. 15

It will appear evident that by mounting said shoe system upon a wheel, as described, said wheel will "take" any snowy and icy road, as the H-shaped and V-shaped members consisting the main characteristics of said shoe, will in turn 20 engage and form a solid grip upon any snowy and icy road.

It is obvious that changes may be made in the form, construction and arrangement of the several parts, as shown, within the scope of the appended claims, without departing from the spirit of the invention, and I do not therefore wish to limit myself to the construction and arrangement shown and described herein. 25

What I claim as new, and desire to secure by Letters Patent of the United States, is:—

1. In a device of the class described, a traction wheel, shoe members mounted upon the edge of the latter and comprising a bifurcated body portion, a sharp-edged block member opposite said bifurcated portion and threaded into the latter, a V-shaped tapered section integral with said bifurcated portion, short rods depending from and integral with said V-shaped portion, and short cylindrical tubes integrally secured at the lower ends of said rods and adapted for attachment to the peripheral edge of said wheel. 35

2. In a device of the class described, a traction wheel, shoe members mounted upon the edge of the latter and comprising a substantially 45 H-shaped, sharp-edged gripping member, a bifurcated section adjacent said gripping member and attached thereto, the forked sections of the bifurcated member being formed with apertures therein for securing said sections to the wheel, a substantially V-shaped, tapered section integral with said former parts, a rod integral with and depending from each wing of said V-shaped member, and short cylindrical tubes forming an integral part with said rods, and being adapted to 50 55

engage the edge portion of the wheel, and fastening means for securing said tubes to the latter, substantially as shown and described.

3. In a device of the class described, a traction wheel, shoe members mounted upon the edge of the latter and comprising a bifurcated body portion, a sharp-edged block member opposite said

bifurcated portion threaded into the latter, a V-shaped tapered section integral with said bifurcated portion, and means for securing said V-shaped member to the edge of a wheel, substantially as and for the purpose set forth. 5

KARL JOHAN ENGELBERT NILSON.
